UNITED STATES PATENT OFFICE.

HUBERT KRANTZ, OF NEW YORK, N. Y.

ELECTRICAL DEVICE.

SPECIFICATION forming part of Letters Patent No. 788,917, dated May 2, 1905.

Application filed December 6, 1904. Serial No. 235,737.

To all whom it may concern:

Be it known that I, HUBERT KRANTZ, a citizen of the United States, and a resident of New York city, borough of Brooklyn, Kings county, State of New York, have invented Improvements in Electrical Devices, of which the following is a specification.

This invention relates to electrical switch mechanism.

In an application filed of even date with this application I have shown, described, and claimed an improved panel-board in which fuses are connected directly to cross-bars that have fuse-connecting points substantially within the limits of the space occupied by the bus-bars, but at a safe distance from the bus-bars in the direction at right angles to the plane of the bus-bars.

In the present invention I provide a combined fuse-connection piece and switch contact-blade adapted for use with this form of panel-board when knife-switches are to be placed on the board. However, I do not limit the present invention to any particular form of panel-board, and my improved connection and blade device may be used for other connections than fuses.

In the accompanying drawings, Figure 1 is a face view of a switch-board provided with one form of my improved connection and contact blade-piece. Fig. 2 is an end view of Fig. 1 looking from the right-hand side. Fig. 3 represents the blank from which the connection and contact-blade piece shown in Figs. 1 and 2 is made. Fig. 4 is a plan view, and Figs. 5 and 6 side elevations, of the device made from the blank shown in Fig. 3. Fig. 7 represents a blank from which a modified form of connection and blade piece may be made, Fig. 8 being a plan, and Figs. 9 and 10 side elevations, of the device made from this blank. Fig. 11 represents a blank for further modification, and Fig. 12 shows a portion of a switch mechanism provided with a device made from the blank shown in Fig. 11.

Referring to Figs. 1 and 2, A is the base, upon which the bus-bars B B' are placed, and C C' C'' C''' are cross-bars raised above the bus-bars and ending approximately flush, crosswise, with the bus-bars. My improved

device is shown at D in Figs. 1 and 2, and this form is separately shown in Figs. 3 to 6. The blank 1, Fig. 3, is cut on line 2 and bent on lines 3, 4, and 5, so that there is formed a base d, adapted to be secured to the base A, 55 Fig. 2, an upright side d', a bent-over top d'', to serve for a raised connection-plate, such as for a fuse E, Figs. 1 and 2, and an upright d'', that forms a contact-blade for a knife-switch, such as F, Figs. 1 and 2. This gives 60 a device that occupies but a very small portion of the panel-board base in the direction in which every bit of space counts.

Fig. 7 shows a rectangular blank 10 cut on line 11 and bent on lines 12 and 13 to form a 65 base h, a straight upright wall h', a bent-over top h'', and an ogee wall h''' rising above the portion h''. It will be evident that if this form of device is substituted for the device D that h will be secured to the base A, one 70 end of the fuse E will be connected to the part h'', and the top of the wall h''' will serve as a contact-blade for the switch F.

Fig. 11 illustrates a blank D' for a connection-piece the same as D, Figs. 1 and 2, except that the upright wall for the contact-blade has a projecting portion d⁵ to enable a switch F', Fig. 12, pivoted near the panel-base A' to make proper contact therewith.

Various slight modifications may be made 80 in these metallic connection-pieces, such as varying the outline of the contact-blade part of either blank 1 or 10 in other convenient shapes than that shown in Fig. 11 and bending the blade h''' in other forms than the ogee 85 shown, or not giving it any bend at all, or in other ways without departing from my invention, the main object of which is to provide a device cheaply and easily constructed, having a base, a connection-plate raised above 90 the base to be suitable for certain purposes, such as that herein shown, of connecting a fuse to a cross-bar at a distance above the bus-bars, and an upright side or wall to act as a contact-blade for a switch. 95

I claim as my invention—

1. In electrical switch mechanism, a metallic device having a base, a connection-plate above the base, and an upright switch contact-blade, all in one piece. 100

2. In electrical switch mechanism, a device formed from a single metallic blank cut and bent to form a base, a connection-plate above the base, and an upright switch contact-blade.
- 5 3. In electrical switch mechanism, a device formed from a single metallic flat blank, bent to form a base, an upright side rising from the base, a connection-plate supported by said upright side above said base, and an upright wall rising above the connection-plate to form a switch contact-blade.
- 10 4. In electrical switch mechanism, a device formed from a substantially flat rectangular
- blank, one end being bent at right angles to form a base, the other end being slotted and one part thereof bent at right angles to form a connection-plate above the base, the other part thereof forming a switch contact-blade.
- In testimony whereof I have signed my name to this specification in the presence of two subscribing witnesses.

HUBERT KRANTZ.
